CLAIM

The ornamental design for a connector terminal installation tool, as shown and described.

DESCRIPTION

FIG. 1 is a top front perspective view of a connector terminal installation tool showing my new design;

FIG. 2 is a top rear perspective view thereof;

FIG. 3 is a left side view thereof;

FIG. 4 is a right side view thereof;

FIG. 5 is a top view thereof;

FIG. 6 is a bottom view thereof;

FIG. 7 is a front view thereof;

FIG. 8 is a rear view thereof;

FIG. 9 is a top front perspective view of an alternate embodiment of a connector terminal installation tool showing my new design;

FIG. 10 is a top rear perspective view thereof;

FIG. 11 is a left side view thereof;

FIG. 12 is a right side view thereof;

FIG. 13 is a top view thereof;

FIG. 14 is a bottom view thereof;

FIG. 15 is a front view thereof; and,

FIG. 16 is a rear view thereof.

The broken line immediately adjacent to the shaded area represents a boundary of the claimed design and forms no part thereof. The broken lines depicting the remainder of the connector terminal installation tool show features that form no part of the claimed design.
